NICHE ASSEMBLY SYSTEM AND METHOD

TECHNICAL FIELD

The present disclosure relates generally to niches in stone or stone-like walls for shower and bath enclosures. More specifically, the present disclosure relates to an adjustable and collapsible niche assembly system for incorporation into the construction of a shower or bath enclosure, or similar.

BACKGROUND

A shower niche, as this term is used in the art, is a cavity that is built into a wall of a shower or bath enclosure for an aesthetic or practical purpose, such as to provide shelving for items typically kept in showers (e.g. soap and shampoo). The construction, assembly, and cladding of a shower niche is typically a complicated and time consuming endeavor for a contractor or homeowner.

A recent development is the use of pre-fabricated waterproofed board niches offered by drywall suppliers and others for integration in to a completed and waterproofed shower or bath enclosure rough-in. Although such pre-fabricated assemblies may simplify the installation process, such configurations are not without drawbacks. One such drawback is the difficult and time consuming nature of cladding a niche, whether pre-fabricated or fabricated in situ.

One approach to clad a pre-fabricated board niche, or any niche fashioned in situ, is to use the same modular tile already used in the completed waterproofed shower system. As the tile body is often a different colour than the tile face, several methods are used to prevent tile body exposure, to maintain the niche's aesthetically pleasing appearance. One such method is to cut the abutting tiles at 45 degree angles on both planes of intersection, known as 'mitred' cuts. Another method is to use metal or plastic edge trims designed to conceal the otherwise exposed tile edges. A third method is to use four custom cut and finished ledges, leaving the back wall plate cladded in the same tile as the rest of the shower.

Another option to clad a niche is to use a pre-glued pre-fabricated niche, which may come in a variety of materials including stainless steel, cement pre-cast, and stone laminate. One drawback to using a pre-glued pre-fabricated niche is that it cannot later be modified. A second drawback is that pre-glued pre-fabricated niches are often bulky, and are easily damaged during transportation, storage, and installation. If damaged, the entire niche would typically need to be discarded. The installation process is time consuming, labour intensive, and often costly as a result.

It is often desirable to clad a shower niche entirely in stone, and often to match the stone to other shower tiles or accessories. Stone niches are typically only found in more expensive homes as they are custom cut and assembled by stone shops on an order-to-order basis. The niche pieces are glued together using epoxy resin with a butt joint and the lower ledge is often inclined one to two percent, to promote water drainage.

There is a need for an easily assembled stone niche assembly system that avoids the drawbacks of using pre-fabricated board niches requiring time-consuming cladding, or pre-glued pre-fabricated niches made of other materials that cannot later be modified and are easily damaged during transportation and storage.

SUMMARY

Disclosed herein is a modular stone niche assembly comprising a back wall and four side walls that combine to

form a niche, the back wall having a predetermined thickness, each side wall comprising an interior surface opposite an exterior surface, the interior surface substantially exposed to the interior of the niche, a front edge opposite a back edge, a first end and a second end, a groove formed in the interior surface proximate to the back edge and extending transversely along the length of the side wall, the groove having a depth and a thickness, the thickness of the groove being larger than the predetermined thickness of the back wall and configured to receive the back wall, a ridge between the groove and the back edge, and having a predetermined height based on the stone of the side wall and configured to support the back wall during installation of the niche, wherein the groove is preformed in each side wall ex-situ prior to assembly and installation of the niche.

Further disclosed herein is a modular stone niche assembly wherein the side walls are formed from one of natural or synthetic stone.

Further disclosed herein is a modular stone niche assembly wherein at least one of the first or second ends being adapted for cutting to remove a predetermined length of stone.

Further disclosed herein is a modular stone niche assembly wherein the depth of the groove is predetermined based on and corresponding to the predetermined height of the ridge.

Further disclosed herein is a modular stone niche assembly wherein the depth of the groove is at least 5 mm.

Further disclosed herein is a modular stone niche assembly wherein the groove is preformed prior to packaging of the modular stone niche assembly.

Further disclosed herein is a modular stone niche assembly wherein for at least two of the side walls, at least one of the first end or second end is pre-cut to greater than 90 degrees relative to the back edge to assist with drainage from the niche, once installed.

Further disclosed herein is a method for constructing a stone niche, comprising the use of the modular stone niche assembly above, comprising the steps of: 1) placing an adhesive into the groove of each of the side walls, 2) placing the back wall into the groove of each of the side walls to form the niche, and 3) installing the niche into an enclosure of a predetermined height and width to receive the niche.

Further disclosed herein is a method wherein prior to step (1), at least two of the side walls are cut in-situ to remove the predetermined length of stone.

Further disclosed herein is a method wherein the predetermined length of stone is removed to reduce the height of the niche once assembled.

Further disclosed herein is a method wherein the predetermined length of stone is removed to reduce the width of the niche once assembled.

Further disclosed herein is a method wherein the predetermined length of stone is removed to reduce the width and the height of the niche once assembled.

Further disclosed herein is a method wherein step (3) occurs before the adhesive has set.

Further disclosed herein is a prepackaged kit comprising the modular stone niche assembly of any of the embodiments described above.

BRIEF DESCRIPTION OF THE DRAWINGS

In the following detailed description, reference is made to the accompanying drawings that form a part hereof, and in which are shown, by way of illustration, in specific exemplary embodiments which may be practiced. These exem-

plary embodiments are described sufficient detail to enable those skilled in the art to understand the scope of the disclosure and claims. Other embodiments may be utilized, and structural, logical, and electrical changes may be made.

FIG. 1. is an exemplary embodiment of a perspective view of the collapsed modular stone tile components of the preferred embodiment.

FIG. 2. is a perspective view of an exemplary embodiment the stone niche mid-assembly with the perimeter stone tile components have stabilizing grooves, while the back wall of the niche cavity does not have stabilizing grooves.

FIG. 3. is a perspective view of an exemplary embodiment the assembled stone niche.

DETAILED DESCRIPTION

One embodiment, the stone niche **10** assembly system comprises the modular stone tile components **20** shown in FIG. 1. This embodiment comprises modular stone tile components **20** incorporated in to the construction of the wall **30** of a shower enclosure. It is appreciated, however, that other embodiments may be implemented in natural or synthetic stone sinks, tubs, hoods, backsplashes, furniture niches (such as medicine cabinets, bar niches or the like), or similar. Modular stone tile components **20** are provided for stone niche **10** assembly. In this embodiment, the stone niche **10** assembly system comprises collapsed and adjustable modular stone tile components **20** with stabilizing grooves **50** for ease of assembly and increased adhesive surface area.

The modular stone tile components **20** of the preferred embodiment include a back wall **60**, two side walls **70**, a top wall **80** and a bottom wall **90** (collectively, the end walls **100**). While the preferred embodiment is described for use with stone, the person skilled in the art would appreciate that any natural stone, synthetic stone (such as Corian™, engineered quartz, cultured marble, cultured granite, cultured onyx, or similar), ceramic/porcelain, or other similar material may be used for the niche **10**.

In this embodiment, the length of the side **70** and end walls **100** is predetermined to cooperate to fit the largest niche **10** desired for this embodiment. To accommodate for the largest niche **10**, the components **20** can be assembled as is, but may also be cut down to accommodate for smaller niches **10**, as desired. In this embodiment, the side walls **70** correspond to the length of the long edges of the back wall **60**, while the end walls **100** correspond to the length of the shorter edges of the back wall **60**.

In this embodiment, each of the side **70** and end walls **100** also has a width that is perpendicular to the length when each piece is laid flat. In this embodiment, the width of the side **70** and end walls **100** is equal, and predetermined based on the desired depth of the stone niche **10**. It will be appreciated by the person skilled in the art that one or more of the pieces could have a longer width than the others, for example if it is desired that the bottom wall **90** of the niche **10** protrudes as a ledge of the remaining wall **30** of the shower or bath enclosure **40**.

In this embodiment, each of the side **70** and end walls **100** has a front edge **110** facing the direction of the shower or bath **40**, and a back edge **120** that will be facing away from the shower or bath **40**. Proximate to the back edge **120** of the side **70** and end walls **100** is a groove **50** configured to correspond and receive the back wall **60** when the stone niche system **10** is assembled. The groove **50** runs transversely along the length of the side **70** or end wall **100** and is cut into the surface of the wall **70** or **100** to a depth of 5

to 15 mm. With thicker walls **70** or **100**, the depth of the groove **50** may be deeper. It will be appreciated by those skilled in the art that the groove **50** may also be shallower where the material is more resilient, or as desired for ease of manufacture and assembly. In this embodiment, the groove **50** is formed in the stone prior to packaging of the components **20** using a milling machine for stone. It would be appreciated by those in the art that the formation of a groove **50** with a consistent depth and dimensions requires specialized equipment and is unlikely to be undertaken by an installer of a stone niche on site. In fact, an installer would typically avoid such a step due to the high likelihood of damaging the stone, an expensive material to work with, which would typically mean the entire piece of stone would be discarded (or possibly repurposed).

While the width of the groove **50** may vary, it is preferred that the width corresponds to a distance that comfortably receive the edge of the back wall **60** without the need to pressure the edge into the groove **50**, to ensure ease of assembly and prevent breakage of the stone. In some embodiments, the width may exceed the dimensions of the back wall **60** edge, for example to accommodate for additional adherent, but in the preferred embodiment the back wall **60** is comfortably received by the groove **50** with little extra space.

The depth of the groove **50** is selected based on the material used for the walls **70** and **100**, including the back wall **60**. The depth of the groove **50** will need to be selected to avoid compromising the integrity of the wall **70** or **100** piece, such that more brittle materials may require a shallower groove **50** or a correspondingly thicker wall **70** or **100** piece to accommodate a groove **50** that is thick enough to support the back wall **60** once assembled. A sufficient thickness of material must remain to minimize the likelihood of breakage during assembly and to support the weight of the back wall **60** during installation.

The thickness of the ridge **130** that is formed between the groove **50** and edge of the side **70** or end walls **100** may also vary depending on the nature (including the brittleness and load bearing capacity) of the material. Ultimately, the thickness of this ridge **130** may be used to support the back wall **60** as the assembled niche **10** is lifted and placed into the desired location in the shower or bath enclosure **40**. The person skilled in the art would appreciate that the size and configuration of this ridge **130** may vary, and may be omitted on the side walls **70** provided adequate ridges **130** are included on the end walls **100**, and vice versa.

In an exemplary method of forming a stone niche **10** from the modular stone tile components **20** of the stone niche assembly system, the end walls **100** are first adjusted to the width of the interior niche cavity **140**. The side walls **70** may be trimmed using a wet saw or angle grinder, or similar equipment known in the art, to adjust the height and width of the stone niche cavity **140**. If only adjusting the height of the niche cavity **140**, the side walls **70** are trimmed while the end walls **100** are not trimmed. The back wall **60** is trimmed by the same amount as the end walls **100** when the width of the stone niche cavity **140** is adjusted, and by the same amount as the side walls **70** when the height of the stone niche cavity **140** is adjusted. In this embodiment, trimming of the various components **20** may be done on site based on the specific measurements of the opening in the drywall to receive the niche **10**. The need to have pieces carefully cut off site may therefore be avoided, and any corresponding delay caused by incorrect measurements or replacing components damaged during transport may be avoided.

Once the modular stone tile components **20** have been adjusted to the desired size, the stabilizing grooves **50** are filled with adhesive and the stone tile edges of the back wall **60** component are slid in to the stabilizing grooves **50** on the perimeter components **20**, as shown in FIG. 2. The stabilizing grooves **50** allow the stone niche assembly **10** to be structurally self-supportive in a short period of time, in some instances immediately, even before the adhesive is set, as shown in FIG. 3. The support provided by the stabilizing grooves **50**, and in particular the corresponding ridges **130** toward the back edge **120** of each wall **70** and **100**, allow for less adhesive and also an adhesive with a lower adhesion strength, which may be easier for the installer to work with.

Once assembled, the stone niche **10** may be installed in to the wall **30** of the shower or bath enclosure **40**. With this embodiment, the installation time and labour may be significantly reduced compared to the conventional approach to stone niche construction and installation. This is particularly so if the modular stone tile components **20** do not require trimming, such that the stone niche assembly process may take only a few minutes, compared to hours.

In another embodiment, the side **270** and end walls **200** of the niche **210** may be made of natural or synthetic stone, while the back wall **260** is made from a different or less costly material, such as porcelain or glass tiles, or similar. In this embodiment, once the niche **210** is assembled, and either prior to installation or after installation, decorative tiles **245** are installed on the front face **265** of the back wall (i.e. the face of the back wall **260** exposed to the shower or bath enclosure **40**). For convenience, this may be done with the niche assembly **210** laying flat on the ground for installation once the decorative tile **245** have been set in grout, but the person skilled in the art would also appreciate that the decorative tiles **245** may be installed in the conventional manner once the niche assembly **210** has been installed. With the dimensions of the niche cavity **240** having been predetermined, in this embodiment any tiles **245** that required cutting can be pre-cut off site and/or in advance of installation to improve efficiency.

In a further embodiment, the stone niche assembly system comprises collapsed and adjustable modular stone tile components **20** with stabilizing grooves **50** and the four perimeter components **70** and **100** are pre-inclined one to two degrees to assist with drainage.

In a further embodiment, the stone niche assembly system comprises collapsed and adjustable modular stone tile components **20** with stabilizing grooves **50**, and the four perimeter components **70** and **100** have a small lip and are pre-inclined one to two degrees.

The exemplary method of forming a stone niche **10** from the modular stone tile components **20** of the stone niche assembly system includes adjusting the modular stone tile components **20** to a desired size; filling the stabilizing grooves **50** with adhesive; sliding the stone tile edges in to the stabilizing grooves **50** to form the stone niche cavity **140**; waiting for the adhesive to set; and installing the stone niche cavity **140** into the shower wall **30**.

In another embodiment of the preferred method, the stone niche cavity **140** is installed in to the shower wall **30** prior to the adhesive setting; minimally adjusted after being installed in to the shower wall **30**; and left to dry after installation.

In another embodiment of the preferred method, the reverse, rough side of the back wall component **60** is kept exposed during the stone niche **10** assembly, allowing for later cladding of the back wall component **60** using decorative tiles **45**, or similar.

While the above description contains many specifics, these should not be construed as limitations on the scope of the claims, but rather as exemplifications of one or another preferred embodiment thereof. The scope of the invention should be determined by the scope of the appended claims, and not just by the embodiments.

It should be understood that steps or the order of the steps described herein may be altered, modified, and/or augmented and still achieve the desired outcome. Further, the various features and adaptations described in respect of one example or embodiment in this disclosure can be used with other examples or embodiments described herein, as would be understood by the person skilled in the art.

A portion of the disclosure of this patent document may contain material that is or may be subject to one or more of copyright, design, or trade dress protection, whether registered or unregistered. The rights holder has no objection to the reproduction of any such material as portrayed herein through facsimile reproduction of this disclosure as it appears in the Patent and Trademark Office records, but otherwise reserves all rights whatsoever.

As used herein, the terms "comprises", "comprising", "includes", "including", "has", "having" or any other variation thereof, are intended to cover a non-exclusive inclusion. For example, a process, method, article, or apparatus that comprises a list of elements is not necessarily limited to only those elements but may include other elements not expressly listed or inherent to such process, method, article, or apparatus. Further, unless expressly stated to the contrary, "or" refers to an inclusive or and not to an exclusive or. For example, a condition A or B is satisfied by any one of the following: A is true (or present) and B is false (or not present), A is false (or not present) and B is true (or present), and both A and B are true (or present).

Also, use of the "a" or "an" are employed to describe elements and components of the disclosed apparatus. This is done merely for convenience and to give a general sense of the disclosed apparatus. This description should be read to include one or at least one and the singular also includes the plural unless it is obvious that it is meant otherwise.

Throughout the specification, terms such as "may" and "can" are used interchangeably. Use of any particular term should not be construed as limiting the scope or requiring experimentation to implement the claimed subject matter or embodiments described herein.

Further, while the specification may have articulated specific technical problems that are addressed by the disclosure and claims, the disclosure is not intended to be limiting in this regard; the person of ordinary skill in the art will readily recognize other technical problems addressed by the disclosure and claims. Unless otherwise defined, all technical and scientific terms used herein have the same meaning as commonly understood by one of ordinary skill in the art to which this disclosure belongs. Although methods and materials similar or equivalent to those described herein can be used in the practice or testing of the presently disclosed embodiments, suitable methods and materials are described below. In case of conflict, the present specification, including definitions, will control. In addition, the materials, methods, and examples are illustrative only and not intended to be limiting.

What is claimed is:

1. A modular stone niche assembly comprising:
a back wall and four side walls that combine to form a niche, the back wall having a predetermined thickness, each side wall comprising:

- an interior surface opposite an exterior surface, the interior surface substantially exposed to the interior of the niche,
  - a front edge opposite a back edge,
  - a first end and a second end,
  - a groove formed in the interior surface proximate to the back edge and extending transversely along the length of the side wall, the groove having a depth and a thickness, the thickness of the groove being larger than the predetermined thickness of the back wall and configured to receive the back wall,
  - a ridge between the groove and the back edge, and having a predetermined height based on the stone of the side wall and configured to support the back wall during installation of the niche,
  - wherein the groove is preformed in each side wall ex-situ prior to assembly and installation of the niche.
2. The modular stone niche assembly of claim 1, wherein the side walls are formed from one of natural or synthetic stone.
3. The modular stone niche assembly of claim 1, wherein at least one of the first or second ends being adapted for cutting to remove a predetermined length of stone.
4. The modular stone niche assembly of claim 1, wherein the depth of the groove is predetermined based on and corresponding to the predetermined height of the ridge.
5. The modular stone niche assembly of claim 1, wherein the depth of the groove is at least 5 mm.
6. The modular stone niche assembly of claim 1, wherein the groove is preformed prior to packaging of the modular stone niche assembly.

7. The modular stone niche assembly of claim 1, wherein for at least two of the side walls, at least one of the first end or second end is precut to greater than 90 degrees relative to the back edge to assist with drainage from the niche, once installed.
8. A method for constructing a stone niche, comprising the use of the modular stone niche assembly of claim 1, comprising the steps of:
- 1) placing an adhesive into the groove of each of the side walls,
  - 2) placing the back wall into the groove of each of the side walls to form the niche, and
  - 3) installing the niche into an enclosure of a predetermined height and width to receive the niche.
9. The method of claim 8, wherein prior to step (1), at least two of the side walls are cut in-situ to remove the predetermined length of stone.
10. The method of claim 9, wherein the predetermined length of stone is removed to reduce the height of the niche once assembled.
11. The method of claim 9, wherein the predetermined length of stone is removed to reduce the width of the niche once assembled.
12. The method of claim 9, wherein the predetermined length of stone is removed to reduce the width and the height of the niche once assembled.
13. The method of any claim 9, wherein step (3) occurs before the adhesive has set.
